SPRINKLING FENCE

Gale Speights, W. 3428 Walton, Spokane, Wash.

Filed Aug. 26, 1957, Ser. No. 680,330

5 Claims. (Cl. 137—356)

The present invention relates to improvements in a 15 sprinkling fence.

The so-called chain link wire fence, which includes metal upright fence posts, a tubular metal top rail, and a woven wire barricade, has come into wide usage in recent years for residential, commercial, and agricultural purposes. In many instances fences of this type are utilized to enclose areas such as lawns or fields which must be sprinkled, irrigated, or otherwise provided with water for the crop grown therein. In order to supply water to these enclosed areas it is presently necessary to utilize expensive sprinkling or irrigating apparatus. It is the purpose of this invention to utilize the existing tubular top rail of the fence as a water carrying sprinkler pipe, thereby doing away with the additional pipes or hose now commonly in use.

More specifically it is the purpose of this invention to provide a combination enclosure fence and sprinkler system which includes spaced apart upright fence posts, a tubular top rail supported on said posts, sprinkling devices mounted on said top rail at spaced apart intervals, and means for supplying water under pressure to said top rail.

A further purpose of the invention is to provide novel fittings for the top rail whereby it may be mounted to a post and connected to a water supply pipe alongside the post by the same member.

A further purpose of the invention is to provide novel corner fittings for said top rail for securing two perpendicularly extending top rails to a corner post, and for joining said top rails in liquid communication.

The nature and advantages of my invention will appear more clearly from the following description and the accompanying drawings, wherein a preferred form of the invention is shown. It should be understood, however, that the description and drawings are illustrative only, and are not intended to limit the invention except insofar as it is limited by the claims.

In the drawings:

Figure 1 is a perspective view of a fence embodying my invention;

Figure 2 is an enlarged fragmentary elevational view of a portion of the fence, illustrating one of the sprinkler heads mounted on the tubular top rail;

Figure 3 is an enlarged plan sectional view illustrating the novel coupling member utilized at the corners of the fence;

Figure 4 is a perspective view of the corner coupling illustrated in Figure 3;

Figure 5 is a sectional view taken substantially on the line 5—5 of Figure 3; and

Figure 6 is a perspective view of the novel coupling member used to connect a water supply to the top rail and to connect the top rail to an end post.

Referring now to the drawings, I have shown in Figure 1 a chain link fence 10, which comprises a plurality of tubular top rail members 11, 12 and 13, each supported by a number of upright posts 14 driven into the ground.

2

The top rail members 11, 12 and 13, and the fence posts 14 support woven wire barricades 15. Corner posts 16 are provided to support the tubular top rails 11, 12 and 13 at the corners of the fence. The fence 10 may also 5 include spaced apart gate posts 17 which support a gate 18 therebetween. According to my invention, I provide sprinkler heads 19 along the top rails 11, 12 and 13, at spaced intervals. I have shown in Figure 1 of the drawings three different types of sprinkler heads 19 which are 10 suitable for my purpose. It will be understood that in a given installation, a single type of sprinkler head 19 can be used throughout the fence. The particular type of sprinkler head 19 used in any installation will depend upon the needs, and conditions existing at that particular installation. Any sprinkler head capable of receiving water from the delivery pipe and spraying it out over a large area is sufficient.

As shown in Figure 2, the sprinkler heads 19 are supported at the upper ends of riser pipes 20, mounted on 20 T-couplings 21 inserted in the top rails 11, 12 and 13. Shut off valves 22 are interposed in the riser pipes 20 between the T-couplings 21 and the sprinkler heads 19 to control the flow from the sprinkler heads 19. It will be appreciated that while I have shown a shut off valve 25 22 for each of the sprinkler heads 19, this may not be necessary in certain installations, and it may be sufficient to insert shut off valves 22 in the tubular top rails 11, 12 and 13 to control a plurality of sprinkler heads 19, or it may be sufficient to insert one main shut off valve in 30 the water supply line for the tubular top rails.

As illustrated in Figure 1, each of the top rail members 11, 12 and 13 extend from one corner post 16 to another. In order to form the top rail members 11, 12 and 13 into a unitary water carrying system, it is necessary to provide means at the corner posts 16 to connect 35 two perpendicular extending top rail members in fluid communication. To accomplish this, I provide novel corner couplings 23, best shown in Figures 3, 4 and 5. Each of the corner couplings 23 comprises two perpendicularly extending cap members 24 and 25 which have internally threaded portions 26 and 27 at their outer ends. The cap members 24 and 25 are connected together and held in perpendicular relation by a short curved tubular portion 28 which extends therebetween. As best shown 40 in Figure 3, the tubular portion 28 joins the cap members 24 and 25 in fluid communication with each other. The top rail members, such as those shown at 12 and 13 in Figure 3, are threaded into the portions 26 and 27 of the end caps 24 and 25, and are thus 45 placed in liquid communication with each other through the curved portion 28. To support the corner couplings 23 to the corner posts 16, I provide the end caps 24 and 25 with axially extending ears 29 and 30. As shown in Figures 4 and 5, the ear 29 on the end cap 50 24 is offset upwardly from the center line of the end cap 24 and the ear 30 and the end cap 25 is offset downwardly from the center line. An upper clamping strap 31 is provided around the corner posts 16 and connected to the ear 29 by a bolt 32. A lower clamping strap 33 55 is provided around the pipe 16 directly beneath the clamping strap 31, and is secured to the ear 30 by a bolt 34. In this manner the corner coupling 23 is rigidly fixed to the corner post 16 to support the ends of the two tubular top rail members 12 and 13.

60 Water is supplied to the fence 10 from an underground water main 35 which extends outwardly from the water supply source to a point beneath the fence 10. A vertical connection pipe 36 is connected to the pipe 35 beneath the fence 10 and extends upwardly to a coupling 37 provided in one of the tubular top rail members 11, 12 or 13. Water is supplied through the connection pipe 36 to 65

the top rail members 11, 12 and 13, and through them to the several sprinkler heads 19. The couplings 37 may be inserted anywhere along the fence that is convenient. In those cases where gate 18 is provided in the fence 10, the water supply main may be extended to the fence near the gate 18, and two connection pipes 36 may be extended upwardly on either side of the gate 18 to supply water to the top rails at each side thereof.

The novel coupling members 37, as shown, connect the water supply from the pipes 36 to the top rails 11. They 10 also connect the top rails 11 to the posts 17. Each member 37 has one end closed and provided with an extended ear 38 which is connected to a clamping strip 39 which is like the clamping strips 31 and 33. The clamping strip 39 is bolted to the ear 38 by the screw bolt 40 which tightens the strip 39 to the post 17. The lateral threaded portion 41 of the member 37 receives the pipe 36. When used only to connect a top rail 11 to a post such as 17, the member 37 may have its portion 41 plugged by a stop plug 42.

It should be apparent from the foregoing that my invention provides a novel sprinkler fence which acts not only as a barricade to enclose an area of ground, but also as an efficient sprinkler system to provide water for the enclosed area. By providing means for joining the existing tubular top rails of the fence 10 in liquid communication, and by utilizing these top rails as the water carrying means for the sprinkler system, I have done away with the expensive hose and pipes formerly necessary.

It is believed that the nature and advantages of my invention appear clearly from the foregoing.

Having thus described my invention, I claim:

1. The combination with a fence having upright posts and tubular top rail members, of terminal couplings at the ends of said tubular top rail members adjacent certain posts, said terminal couplings each having threaded connection with the tubular member at one end and having the other end closed, an ear extending from the closed end, and clamp means around the adjacent post secured to said ear, one of the terminal couplings having a lateral tubular projection thereon intermediate its ends connected to a water conduit.

2. The combination with a fence having upright posts and tubular top rail members, of terminal couplings at the ends of said tubular top rail members adjacent certain posts, said terminal couplings each having threaded con-

nection with the tubular member at one end and having the other end closed, an ear extending from the closed end, and clamp means around the adjacent post secured to said ear, certain of the terminal couplings having lateral tubular projections thereon intermediate their ends, said tubular projections being joined to another tubular member extending transversely to the post coupled tubular rail member.

3. Means for connecting tubular rail members and a corner post of a fence to each other to support the rail members and to provide passage for water from one rail member to another past said corner post, said means comprising a pair of hollow cap members each having one end closed and the other end thereof open and threaded to receive a tubular rail member, said cap members having means thereon for attaching them to the corner post, and a tubular pipe section having one end joined to one cap member and the other end joined to the other cap member, said tubular pipe section holding the cap members 20 at an angle to each other and providing liquid passage from one cap member to the other.

4. The invention defined in claim 3 wherein the means on the cap members for attaching them to the corner post comprise an ear projecting from the closed end of each cap member and a post clamp attached to each ear.

5. The invention defined in claim 3 wherein the means on said cap member for attaching them to the post comprise an upwardly offset ear on the closed end of one cap member, and a downwardly offset ear on the closed end 30 of the other cap member.
